UNITED STATES PATENT OFFICE.

JOSEPH WM. LE MAIRE AND HARRY L. WILLIAMS, OF NEW YORK, N. Y.

PRIMING DEVICE.

1,282,015.

Specification of Letters Patent. Patented Oct. 15, 1918.

Application filed April 23, 1918. Serial No. 230,251.

To all whom it may concern:

Be it known that we, JOSEPH WM. LE MAIRE and HARRY L. WILLIAMS, citizens of the United States, and residents of the city 5 of New York, in the county of New York and Queens, respectively, and State of New York, have invented certain new and useful Improvements in Priming Devices, of which the following is a specification.

10 The present invention relates to improvements in starting devices for internal combustion engines, and more particularly to that type of starting devices which is intended to be used with engines upon motor 15 vehicles, although it will be understood that it is applicable to engines used in other connections.

The main object of the present invention is to provide an improved device, by the 20 use of which a sufficient amount of gasolene, to prime the engine, may be introduced into the cylinders of the engine, without the necessity of opening the hood of the motor vehicle to turn the pet-cocks of the various 25 priming cups.

A further object of the invention is to provide a device of the character specified which is conveniently accessible to the driver without leaving his seat, the device being of 30 such a character that it may be operated by simply pulling a handle located in front of the driver's seat.

A still further object of the invention is to provide a device of this type which may be 35 applied easily to existing motor vehicles as well as to new vehicles, and which is relatively inexpensive and adapted for manufacture on a commercial scale.

With these and other objects in view, 40 will more fully appear as the nature of the invention is better understood, the same consists in the combination, arrangement, and construction of parts hereinafter described, pointed out in the appended claims and 45 illustrated in the accompanying drawings, it being understood that many changes may be made in the size and proportion of the several parts and details of construction within the scope of the appended claims without 50 departing from the spirit or sacrificing any of the advantages of the invention.

One of the many possible embodiments of the invention is illustrated in the accompanying drawings, in which:—

55 Figure 1 is a side elevation of a priming device constructed in accordance with the

present invention; Fig. 2 is a longitudinal vertical section taken therethrough; Fig. 3 is a top plan view of the same with some of the elements in other positions; and Fig. 4 is a section taken on line 4—4 of Fig. 2.

In the drawings, the numeral 10 indicates a reservoir, adapted to contain a suitable liquid hydrocarbon, such as gasolene, which is filled into the said reservoir through a 65 nipple 11, covered by a cap 12, the latter being provided with a vent hole 12'. This reservoir is attached in any suitable manner to the dash-board, when the engine is applied to a motor vehicle, and is, preferably, disposed below the hood of the vehicle. The reservoir is provided with a small fuel outlet 13, communicating with the cylinder 14 of a pump, that is shown in the drawings as being made integral with the said reservoir, 70 although it may be secured thereto in any suitable manner. The pump cylinder extends through an opening 15 in the dashboard 16, and is provided with a rear head 17 and a front head 18. A little distance in 75 rear of the front head 18 there is formed in the cylinder a partition 19, extending at right angles to the longitudinal axis of the said cylinder and dividing the same into a piston chamber 20 and a compartment 21, 80 the latter communicating through the fuel outlet 13 with the reservoir 10. The partition 19 has an opening 22, through which the piston chamber communicates with the compartment 21. In the front head 18 is formed 85 a perforation 23, with which co-operates an inwardly opening spring-pressed check valve 24, for a purpose hereinafter to be described.

In the piston chamber is mounted a piston 90 25 of any suitable construction, the said piston being secured to a piston rod 26, that extends through the rear head 17 and terminates in a handle 27. To this handle and to the rear head 17 are attached helical 100 springs 28, which have a tendency to hold the piston in its forward position, that is to say at the beginning of its suction stroke.

The compartment 21 is provided with a discharge opening 29, controlled by a cock 105 30, the outlet of which is connected by a pipe 31, preferably, with the manifold of the internal combustion engine, with which the priming device is intended to co-operate. To the plug 32 of the cock 30 is pivoted 110 at 33 an actuating bar 34, that extends rearwardly in parallel relation to the piston rod

26 through the dash-board 16, and is provided with an arm 35, the latter being seated in a longitudinal slot 36 in the piston rod, the arrangement being such that, when the 5 piston is in its forward position (Fig. 2), the arm 35 abuts against the rear edge 37 of the slot 36 and the cock is in its closed position. The slot 36, on the other hand, is of a length that its front edge 38 comes 10 into contact with the arm 35 immediately before the piston completes its suction stroke, thereby shifting the said arm as the suction stroke is being completed and thus partially turning the plug 32 of the cock 20 15 so as to open a communication between the discharge opening 29 and the pipe 31.

The operation of this device is as follows:—Assuming that the piston is in its forward position (Fig. 2), obviously the 20 check valve 24 is held by its spring in its closing position. As the piston is drawn rearwardly, the said check valve is unseated, so that air will be drawn into the compartment 21 and piston chamber 20, which air 25 will vaporize the fuel therein. The cock 30 is held in its closed position until the piston has nearly completed its suction stroke and until the arm 35 comes into contact with the front edge 38 of the slot 36 in the piston 30 rod 26, when, upon completing the suction stroke, the said piston rod causes the actuating bar 34 to move with it, thereby giving a partial turn to the cock plug 32 and opening a communication between the compartment 21 and the pipe 31. As the piston is 35 moving on its suction stroke, the springs 28 are obviously expanded. If, therefore, upon the completion of the suction stroke of the piston the handle 27 is left free, the springs 40 28 will cause the said piston to move in the opposite direction, that is to say upon its expelling stroke. As soon as the expelling stroke is started, the check valve 24 closes the perforation 23, and the fuel within the 45 pump cylinder is injected into the pipe 31, the cock being left open until the rear edge 37 of the slot 36 comes into contact with the arm 35 of the actuating bar 34 and shifts the cock plug during the continued movement of the piston into its closing position.

In the pipe 31 the fuel flows into the intake manifold, from which it is drawn into the cylinders of the engine.

Although a single operation of the primer should be sufficient under ordinary conditions, the operation can be repeated as often as desired according to the requirements. It is to be observed that a measured quantity of fuel is fed during each operation to the engine cylinders, the quantity depending upon the size of the pump cylinder.

What we claim is—

1. A priming device for internal combustion engines, including a cylinder having an inlet opening communicating with a supply of liquid hydro-carbon and a valve controlled discharge opening, a piston in said cylinder, a piston rod fixed to said piston having a longitudinal slot, an actuating bar pivoted to the valve controlling said discharge opening having an arm extending into said slot, whereby said valve is brought to its open position near the end of the suction stroke of said piston in said cylinder and to its closed position at the end of the stroke of said piston in the opposite direction.

2. A priming device for internal combustion engines, including a reservoir for containing a supply of liquid hydro-carbon, a cylinder having a piston chamber and a compartment communicating with said chamber and with said reservoir, said compartment being provided with a valve controlled discharge opening, a piston in said chamber, a piston rod fixed to said piston having a longitudinal slot, an actuating bar pivoted to the valve controlling said discharge opening having an arm extending into said slot, whereby said valve is brought to its open position near the end of the suction stroke of said piston in said cylinder and to its closed position at the end of the stroke of said piston in the opposite direction.

Signed at New York, in the county of New York, and State of New York, this 18th day of April, A. D. 1918.

JOSEPH WM. LE MAIRE.
HARRY L. WILLIAMS.
